MAURICE J. STACE, OF COHOES, NEW YORK, ASSIGNOR TO BRINTNALL MANUFACTURING COMPANY, INC. OF DELAWARE, OF WILMINGTON, DELAWARE, A CORPORATION OF DELAWARE.

METHOD OF PREPARING COTTON BATTING FOR SHIPMENT AND USE.

Application filed October 7, 1926, Serial No. 140,138, and in Canada March 27, 1925.

My invention has for its object to provide a new and improved method of preparing and handling cotton batting used in automobile and similar upholstery and to prepare 5 the same for shipment and use in a more efficient and economic manner than has heretofore been possible and by the use of which a more perfectly conditioned finished product is made possible and a very great 10 saving of shipping and storage space effected.

According to the practice before my invention cotton batting was prepared by taking a sheet of batting and folding it over 15 upon itself longitudinally into a continuous bat, the folding being done around an insert or core of paper, fabric, or other material. In some forms of bats a double folding method is used and the paper strip is employed to gum the folds together. In all 20 methods heretofore used, however, the bat when it comes from the folding machine is of a more or less elliptical cross section. In the method now most commonly used for 25 shipping bats the bat is laid zigzag fashion in a narrow box by a back and forth movement which alternately brings the last fold of the bat on top and underneath so that in making the bend from one fold to another 30 the bat is frequently opened at the bends or deformed resulting in an unsatisfactory condition when the bat is removed from the package for stuffing into pleats.

It is one of the objects of my present invention to eliminate the above mentioned 35 objectionable features and to so condition the bat after it leaves the forming machine that when it is unwound for use the bat will be compact and instead of an elliptical cross 40 section it will be retained in approximately a rectangular cross section.

Again it is the object of the invention to provide a method of baling the bat whereby 45 all danger of deforming the bat and the folds of the bat slipping on each other or coming loose or opening up is eliminated.

The method which constitutes the subject matter of my invention will be clearly understood by those skilled in the art from the

description following and taken in connection with the accompanying drawings in which:—

Figure 1 is a somewhat diagrammatic perspective view illustrating the manner in which the cotton batting is taken from the 50 folding machine in its partially completed sheet and wound into a roll or cylindrical bat constituting one of the steps of the present method.

Figures 2 and 3 are perspective views of 55 a roll of batting formed as indicated in Figure 1 as viewed from the side and end respectively.

Figure 4 illustrates diagrammatically the 60 manner in which pressure is applied to a plurality of rolls of batting to perform the dual function of constraining the mass to a greatly reduced shipping volume and providing the primary step toward the ultimate shaping of the lengths of batting to the desired substantially rectangular and relatively flat cross sectional shape.

Figure 5 illustrates diagrammatically the 65 manner in which the constrained mass of batting rolls are securely retained in their 70 volume reduced batting length pressed condition for being stored and shipped so that the fibres of the batting will become set to the desired condition because of such confinement and storage before or during shipping 75 or during both.

Figure 6 illustrates a completed bale of 80 batting rolls ready for storage and shipping.

Figure 7 illustrates the contents of a bale 85 of batting rolls after shipment.

Figure 8 illustrates a roll of batting 90 mounted for facilitating the paying-off of the batting length without tensile strain on the fibres thereof.

Figure 9 illustrates in diagrammatic cross 95 section a portion of the continuous batting length and shows the primary condition of the same as it leaves the forming machine.

Figure 10 is a view similar to Figure 9 and illustrates a section of batting completed 95 by use of my improved method and ready for use.

Figure 11 is a view similar to Figure 9 il-

lustrating another type of folded bat as it comes from the folding machine in its primary or partially completed condition.

Figure 12 is a view similar to Figure 10 5 illustrating the bat shown in Figure 11 after it has been completed, i. e., the condition the bat is in when it is being unwound in the manner indicated in Figure 8.

In the drawings, 1 represents the bat 10 forming machine which may be of the general construction of that disclosed in my patent No. 1,496,952, issued June 10, 1924 and which is adapted to take a sheet of cotton batting, fold it longitudinally on itself into 15 the cross sectional form indicated in Figure 9, or into other cross sectional forms such for instance as that indicated in Figure 11. When the bat comes from the forming machine in its folded condition it is more or 20 less resilient and assumes an approximately elliptical form in cross section, see Figure 9, see dotted lines also in Figure 11. As the bat comes from the folding machine the last-fold is on top, that is to say, the last fold 2' 25 of the continuous bat 2 lies uppermost, or the double fold 2^x—2^x in Figure 11 lies uppermost. The loosely folded bat usually contains a paper or other insert strip 2^z which may be gummed or not as desired. If 30 the fold indicated in Figure 11 is used the strip is gummed to tend to hold the bat from unfolding.

As the batting length 2 leaves the discharge end of the forming machine 1 it 35 passes over supporting rollers 3, between which a compensating loop 4 is permitted to depend in the manner indicated in dotted lines in Figure 1 of the drawings, and it is then wound spirally in edge to edge layers 40 around a hollow core 5 into the form of a cylindrical roll 6 as indicated in Figures 1, 2 and 3. It will be understood, of course, that the depending loop 4 is made in the batting being rolled during the early portion of 45 the rolling action to compensate for the increasing speed of take-up on the roll core 5 due to the ever increasing circumferential wrapping surface of the roll.

For accomplishing the above mentioned 50 winding any suitable apparatus such as is indicated in Figure 1 of the drawings may be utilized. In that illustration, 7 indicates a feeding horn through which the advance end of the batting length is threaded and 55 which is caused alternately to traverse the length of the core 5 from end to end, bobbin winding fashion, to effect the proper guiding of the winding function. A frame 8 serves to support the apparatus which includes the vertical guideway equipped roll end confining wings 9 and the roll supporting and rotating rollers 10, a pair of the latter of which are provided and spaced apart 60 to sustain the roll thereupon and to which

rotation is imparted to facilitate the rolling 65 action, through the medium of the power transmission devices 11. A rigid shaft 12 is, of course, inserted through the core 5 as a mandrel to project from the ends thereof and provide trunnions for the roll and co- 70 operate with the guideways of the wings 9. This roll feature provides for the desired perfectly normal condition of the batting throughout the entire length thereof and entirely eliminates all twisted, matted and 75 swollen portions which would greatly reduce the commercial value of the batting.

By winding the batting on the core with the "last fold" side or face adjacent the mandrel all tendency of the last fold to become 80 displaced from the remainder is avoided as the tendency is to hold the last fold down against slippage. While, of course, the bat may be rolled with the other side adjacent the core, nevertheless better results are obtained by rolling the last fold side facing the core.

In rolling the bat on the core no tension is applied for the purpose of compacting the mass or effecting a tight winding. On the other hand the winding is a loose winding so 90 as not to stretch or elongate the fibres of the bat.

When bats having the cross section of 95 Figure 11 are wound it is especially advantageous to wind them with the last-fold-side 2^x—2^x facing the core for otherwise practice has demonstrated that when the bat is wound on the core with the last-fold-side 100 away from the core there is a tendency for the bat to open up centrally and spread apart, thus deforming the bat and often rendering it unfit for piping. By winding the bat with the folds 2^x—2^x facing the core the forces acting during winding are so directed 105 as to keep the folds closed along the middle line and prevent separation or loosening of the cotton from the gummed strip 2^z, particularly if the glue is still soft as it frequently is when the manufacturing and 110 winding operations take place rapidly.

One or more of the rolls, formed as above described are then placed in a press or baler as indicated in Figure 4 of the drawings and pressure is applied thereto to reduce the volume of the mass of the roll to a relatively small mass, or in other words, to change the roll from a large diameter roll bale to a smaller cross section square or angular bale. The purpose of this is twofold, 115 namely, to adapt the bale to occupy a small storage or shipping space and also to impart to the batting lengths the final finished pressure designed to effect the final cross sectional shape and dimensions of the desired completed product. The baler illustrated is 120 of the vertical pressure type and is very convenient in that the burlap or other baling

material may be positioned one sheet above and one below the product and one at each side thereof, and, after pressure has been applied to the desired degree, the ends of the material are drawn together by sewing or otherwise so that when pressure is released the compressed mass will be held in its confined condition.

The constricting of the mass from the large diameter roll bale to the smaller cross sectional square bale is done while the core 5 remains in place and provision is made to prevent the elongation of the bale in the direction of its axis. Thus when the bale is mounted on the unwinding stand and the burlap cover removed the bat when unwound from the bale instead of being a loose resilient mass of approximately elliptical cross section which would not hold its form, the bat comes from the roll in the condition illustrated in Figures 10 and 12, namely a compacted flat bat, the compacting pressures also serving to cause the fibres of adjacent layer surfaces to interlock or interengage as it were, thereby aiding in preventing the unwinding of the bat as it is drawn from the roll and fed into the stuffing tool.

It should be understood, of course, that when the compressed bale is released from its burlap covering and put on the stand as shown in Figure 8, it will gradually reassume a cylindrical form but the diameter of the cylinder will not return to the original of the cylinder when first wound as indicated in Figure 1.

The baler which I prefer to use includes the usual confining sides 13, bottom 14, rear wall 15 which may or may not be removable as desired, removable front wall 16, pressure applying top 17, pressure exerting devices 18 and any desired travel distance control devices 19.

After the cylindrical roll has been baled as indicated in Figure 6 the bales are stored for a sufficient time to allow the fibres of the batting lengths to become set to their desired final condition and the final conditioning of the bale is thus effected. This storing may take place in the store room of the manufacturer or in the storage room of the user, or while the goods are in transit, so long as the bat is permitted to remain baled a sufficient length of time to enable the bat fibres to become set to the desired degree in order that when the bat is unrolled it may be in the proper shape for insertion into the pleat pockets.

Figure 5 of the drawings indicates the restrained mass in the partly closed burlap envelope and Figure 6 indicates the completed bale.

When it is desired to use the contents of a bale of batting one thereof is opened, as indicated in Figure 7, from which it will be

seen that the mass retains its constrained condition and that the pressure exerted by the baler has no effect whatever toward collapsing the cores 5 but that the latter are still in their normal condition and adaptable for receiving a piece of shafting for providing means for mounting the individual rolls of batting in the manner indicated in Figure 8.

During the whole of the baling and storage of the batting rolls the process of completing the conditioning of the batting lengths, from that illustrated in Figure 9 to that illustrated in Figure 10, goes on.

When it is desired to use a roll of the batting, it is mounted upon any suitable unwinding stand 20 adaptable for receiving the trunnions forming rod 21 passed through the core 5 of the roll and provided with anti-friction means 22 for supporting that rod to permit free rotation thereof during the paying-off of the batting length from the roll without tensile strain on the fibres thereof, so that the finally complete desired condition of the said batting will not be disrupted.

From the foregoing description it will be seen that I have provided an improved method of preparing cotton bats for shipment and use, by the employment of which not only is a better bat obtained but the freight charges on carload lots are reduced because of the compact nature of the "square" bales.

I am aware that prior to my invention cotton sheeting has been rolled into compact roll bales, the winding being conducted under tension to provide a tightly wound bale. The sheeting is wound around a mandrel or core which is afterwards removed and does not form a permanent part of the bat, (see for example the patent to Davenport No. 729,285 issued May 26, 1903).

I am also aware that prior to my invention it has been proposed to bale cotton by twisting it into a rope of firmly compressed strands and winding such strands under tension upon a shaft into the form of a roll bale, encasing the bale into an envelope and removing it from the shaft (see Motz No. 696,743, issued April 1, 1902).

I am also aware that prior to my invention it has been proposed to twist cotton fibres into a loose rope and wind the same around a mandrel while applying pressure to the coils of the mandrel to compact or effect a tension winding of the material, (see for example the patent to Drake No. 179,849, issued July 18, 1876).

I am also aware that prior to my invention it has been proposed to wind cotton sheeting tightly about a large mandrel to form a cylindrical bale, then removing the bale of sheet cotton from the mandrel and

putting it in a compress to form a compact rectangular or square bale, see for example the patent to Luce, No. 864,975, issued September 3, 1907.

5 In none of the foregoing methods of the prior art, however is the core permitted to remain in the bale and in no instance is a flat folded bat proposed to be wound. I therefore do not claim broadly the winding 10 of cotton into a cylindrical form and then compressing it into a rectangular bale.

The present application in so far as it contains subject matter in common with my application Serial No. 16,078, filed March 15 16, 1925, is a continuation of that application.

What I claim is:

1. The method of preparing cotton for shipment and use, which consists in taking 20 a sheet of cotton, folding the same lengthwise over upon itself loosely to constitute a relatively narrow continuous bat of approximately elliptical cross section, winding the bat flatwise loosely on a core in superposed layers as a round bale, compressing the bale, while maintaining the core in place, into a square bale while holding the bale against spreading along the axis of the core, thereby flattening the entire bat within the 30 bale into a form approximately rectangular in cross section and retaining the compressed bale in its compressed condition until ready for use.

2. The method of preparing cotton for shipment and use, which consists in taking 35 a sheet of cotton, folding the same lengthwise over upon itself loosely to constitute a relatively narrow continuous bat of approximately elliptical cross section, winding the bat flatwise loosely on a core with the last-fold surface of the bat facing the core in superposed layers as a round bale, compressing the bale, while maintaining the core in place, into a square bale while holding the bale against spreading along the 40 axis of the core, thereby flattening the entire bat within the bale into a form approximately rectangular in cross section and retaining the compressed bale in its compressed condition until ready for use.

3. The method of preparing cotton for shipment and use, which consists in taking a 55 sheet of cotton, folding the same lengthwise over upon itself loosely to constitute a relatively narrow continuous bat of approximately elliptical cross section, winding the bat flatwise loosely on a core in superposed layers as a round bale, compressing the bale, while maintaining the core in place, into a square bale while holding the bale against spreading along the axis of the core, thereby flattening the entire bat within the bale into a form approximately rectangular in cross section, enclosing the compressed bale in a 60

retaining envelope for a sufficient period 65 of time until the bat becomes set, whereby when the bat is later unwound from the bale for use it will retain an approximately flattened cross section in lieu of the illiptical cross section it had when first wound. 70

4. The method of preparing cotton for shipment and use, which consists in taking a sheet of cotton, folding the same lengthwise over upon itself loosely to constitute a relatively narrow continuous bat of approximately elliptical cross section, winding the bat flatwise loosely on a core with the last-fold surface of the bat facing the core in superposed layers as a round bale, compressing the bale, while maintaining the core in place, into a square bale while holding the bale against spreading along the axis of the core, thereby flattening the entire bat within the bale into a form approximately rectangular in cross section, enclosing the compressed bale in a retaining envelope for 75 80 85 a sufficient period of time until the bat becomes set, whereby when the bat is later unwound from the bale for use it will retain an approximately flattened cross section in lieu of the elliptical cross section it had when first wound. 90

5. In a method of preparing upholstery cotton bats of the longitudinally folded type for shipment and use, the steps which comprise the winding of the bat loosely around a core thereby producing a loose easily deformable bale, taking said bale and restraining it against elongation in the direction of its axis while holding the core 100 in place, compressing the bale into a rectangular or flat bale without deforming the core, thereby flattening the bat within the bale as well as compacting the mass of the bale and retaining the compressed bale in its 105 compressed condition until ready for use. 95

6. In a method of preparing upholstery cotton bats of the longitudinally folded type for shipment and use, the steps which comprise the winding of the bat loosely around a core thereby producing a loose easily deformable bale, taking said bale and restraining it against elongation in the direction of its axis while holding the core in place, compressing the bale into a rectangular or flat bale without deforming the core, thereby flattening the bat within the bale as well as compacting the mass of the bale, and maintaining the bale compacted for a sufficient time interval to cause the fibres 110 115 of the bat within the bale to set to a degree sufficient to retain a substantial flattened form of bat in cross section whereby when the bat is later unwound from the bale it will be of an approximately flattened cross section in lieu of the elliptical cross section of the bat when first wound. 120 125

7. The method of preparing cotton for

shipment and use, which consists of the following steps in the order mentioned, viz: first, forming the cotton into a loosely folded continuous bat, second, winding the bat flatwise loosely on a small hollow core into a loose cylindrical bale, third, compressing the bale into a compact bale and thereby compacting the material of the bat

within the bale while maintaining the core 10 in place and restraining the bale against displacement in the direction of the axis of the core, fourth, holding the bale in the compressed state for a sufficient time interval to enable the cotton to become "set", substantially as specified.

MAURICE J. STACK.
